Primary Examiner — Michael C Stout*Assistant Examiner* — Nicole M. Leech(74) *Attorney, Agent, or Firm* — Dunlap Bennett & Ludwig, PLLC(57) **CLAIM**

The ornamental design for a bracelet, as shown and described.

DESCRIPTION

FIG. 1 is a top front right perspective view of the bracelet, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown in the drawings depict portions of the bracelet that form no part of the claimed design.

In FIGS. 1-7, the stippling shown reflects a contrast of appearance.

1 Claim, 4 Drawing Sheets(56)
